[57] CLAIM

The ornamental design for a coaxial cable connector, as shown and described.

DESCRIPTION

FIG. 1 is a front and top perspective view of a coaxial cable connector showing our new design;

FIG. 2 is a top plan view of a coaxial cable connector showing our new design on a reduced scale;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof; and,

FIG. 8 is a top, front and side perspective view thereof shown on an enlarged scale. The broken line showing of the coaxial cable and the center core is included for the purpose of illustrating environmental elements only and forms no part of the claimed design.
